United States Patent Office.

JOHN K. McDONALD, OF NEWARK, NEW JERSEY.

Letters Patent No. 76,224, dated March 31, 1868.

IMPROVEMENT IN DOOR AND PACKAGE-HOLDER.

The Schedule referred to in these Letters Patent and making part of the same.

TO ALL WHOM IT MAY CONCERN:

Be it known that I, JOHN K. McDONALD, of Newark, in the county of Essex, and State of New Jersey, have invented a new and improved Hat and Package-Holder and Door-Fastener; and I do hereby declare that the following is a full and exact description of the same, reference being had to the accompanying drawings and to the letters of reference marked thereon.

To a loop, A, I attach a flat piece, B, for the purpose of a door-fastener. The points C C C (there may be more or less of them) are held against the inside of the door-casing, up close to the loop. The door is then shut by the loop, and against this piece, crowding the points into the casing, when the loop is slipped across the edge of the door and casing, and prevents pushing the door open even if it were unlocked. Also, to the loop I attach the hook D with a sharp point. This, with the other hooks, is to be used in travelling in the cars. This hook is made to attach to the back of the car-seat or the lattice of the window-shade, or even to the side of the car. The hook E is especially designed for a hat. The point F catches on to binding of the hat. It may be used for other things. The hook G is designed for any ordinary package. The number of hooks may be increased if desired.

The whole is enclosed with two or three pieces of rubber tubing (see Figure 3,) or it may be put in a small case made of hard rubber, metal, or other material. This simple combination provides a convenient fixture for protecting the door over night, and of disposing of a hat and other small parcels when travelling in the cars. The door-fastener may be made and used separately, as also may the hat and package-holder, if desired.

What I claim as my invention, and desire to secure by Letters Patent, is—

The combination of the piece B, hooks D, E, and G, with the loop A, substantially as and for the purpose specified.

JOHN K. McDONALD.
